Meyer; Joshua B. Goldberg

(57) **CLAIM**

The ornamental design for the a lid for a container, as shown and described.

DESCRIPTION

FIG. 1 is a first perspective view of a lid for a container, showing my new design;

FIG. 2 is a second perspective view thereof;

FIG. 3 is a third perspective view thereof, showing the lid for a container in a position of use with an exemplary container; FIG. 4 is a top view thereof, with the exemplary container removed to show aspects of the design not visible when combined;

FIG. 5 is a bottom view thereof;

FIG. 6 is a side view thereof;

FIG. 7 is an opposite side view thereof;

FIG. 8 is a front view thereof;

FIG. 9 is a rear view thereof;

FIG. 10 is a third perspective view thereof, shown with the cover removed; and,

FIG. 11 is a fourth perspective view thereof.

The broken lines are shown for the purpose of illustrating environmental subject matter of an exemplary container and form no part of the claimed design.

1 Claim, 9 Drawing Sheets
